UNITED STATES PATENT OFFICE.

JOHN F. O'CONNOR, OF CHICAGO, ILLINOIS, ASSIGNOR TO WILLIAM E. MINER, OF CHICAGO, ILLINOIS.

RAILWAY DRAFT-RIGGING.

1,070,058.

Specification of Letters Patent.

Patented Aug. 12, 1913.

Application filed February 5, 1912. Serial No. 675,526.

To all whom it may concern:

Be it known that I, JOHN F. O'CONNOR, a citizen of the United States, residing at Chicago, in the county of Cook and State 5 of Illinois, have invented a certain new and useful Improvement in Railway Draft-Rigging, of which the following is a full, clear, concise, and exact description, reference being had to the accompanying drawings, forming a part of this specification.

My invention relates to improvements in railway draft rigging.

The object of my invention is to provide a draft rigging of strong and durable construction and efficient operation.

My invention in some of its features is an improvement upon my previous invention disclosed in my application for a patent thereon filed in the United States Patent Office on December 9th, 1911, as Serial No. 664,755.

In the accompanying drawings forming a part of this specification Figure 1 is an elevation partly in central longitudinal section of a friction spring draft rigging embodying my invention. Fig. 2 is a plan view partly in horizontal section. Fig. 3 is a horizontal section showing the position of parts within the friction shell and spring cage on preliminary buffing movement with the supplemental spring compressed. Fig. 4 is a horizontal section showing the position of parts in full buff. Fig. 5 is a cross section on line 5, 5 of Fig. 1. Fig. 6 is a cross section on line 6, 6 of Fig. 1. Fig. 7 is a perspective view of the shell showing the friction shell and spring cage integral therewith. Fig. 8 is a perspective view of one of the friction shoes. Fig. 9 is a perspective view of the wedge or spreader block. Fig. 10 is a perspective view of the double faced spring seat.

In the drawings 11 are the draft sills or members of the car frame to which the draft rigging is applied. 12 the end sill. 13 the carry iron. 14 the buffer block. 15 the draw bar. 16 the draft yoke. 17 the carrier plate. 18 rear stop members secured to the draft members or sills, preferably by 50 the rivets 19, and having rear stop shoulders 20.

21 are front stop members having front stop shoulders 22, and limiting stop shoulders 23 and 24.

25 is the front follower.

The rear follower 26 preferably consists of the preferably integral rear end of the shell 27, the shell 27 consisting of a spring cage 28 and a friction cylinder 29, preferably integral with the spring cage. The 60 spring cage 28 is preferably of a general rectangular shape, and contains the preferably side by side arranged spring cushioning members or main springs 30, 30, each of which preferably incloses a smaller 65 spring 31, 31 nested within it. The spring cage 28 is provided with longitudinal slots or openings 32 in its upright faces 33 which fit between the center sills 11, the upright faces of the spring cage serving as guides in 70 its reciprocating movements. The openings 32 permit the insertion into the spring cage of the main springs 30, 30 and 31, 31. The upper and lower horizontal faces 34 and 35 respectively of the spring cage engage the 75 inner face of the draft yoke 16, the lower member of which draft yoke rests upon the carrier plate 17, which thus supports the entire cushioning mechanism of the draft rigging.

The friction cylinder 29 is cylindrical in form or circular in cross section, and has a longitudinal annular friction face 36 which is in sliding frictional contact with the exterior friction face 37 of the segmental friction shoes 38, which are preferably three in number. Each of the friction shoes 38 has an inclined or wedging inner face 39 furnished with a stop shoulder 40, which limits the release position of the anti-friction roller 41, one of which is interposed between each of the friction shoes and the corresponding wedge face 42 of the wedge 43 which abuts against the front follower 25. The wedge is preferably of pyramidal form and with 95 three wedge faces, one for each of the friction shoes, and each inclined face of the wedge has a shoulder 44 to retain the anti-friction roller 41 in its proper transverse arrangement. Each of the friction shoes is 100 also provided with shoulders 45 for engagement with the ends of the anti-friction roller

11 to keep the roller in position lengthwise. The friction cushioning members consisting of the wedge, friction shoes and anti-friction rollers are within the friction shell 29, which is preferably integral with the spring cage 28 forming the shell 27.

The forward corners 48 of the spring cage serve as stop shoulders for engagement with the rear limiting stop shoulders 24 of the front stop members 21. The forward ends 10 of the main springs 31, 31 and 32, 32 engage the rear face 47 of the double faced spring seat 48; the rear face 47 of the spring seat being preferably provided with the 15 bosses 49, 49, around which the inner springs 31, 31 are seated at their forward ends. The forward face of the spring seat 48 is provided with a collar 50 within which the rear end of the supplemental spring 51 is seated. 20 The forward end of the supplemental spring is seated against the annularly arranged segmental friction shoes 38, and preferably against their rear end faces 52.

The double faced spring seat 48 is provided with a central bearing or hub portion 53 containing the perforation 54 for the passage of the short connecting rod 55, which also extends through the perforation 56 in the wedge 43. The wedge 43 is provided at 30 its forward end with a recess 58 suitably constructed to receive the nut 59, which is turned on the threaded forward end of the short connecting rod 55. The rear end of the connecting rod 55 is provided with a 35 head 60, which is received within the recess 61 provided on the rear face of the double faced spring seat.

The front face of the double faced spring seat is provided at either side with the ribs 62, 62, preferably two on either side of the collar 48, the front edges of each of said ribs being provided with an upright groove 63 which registers with a similar upright groove 64 provided in the horizontally disposed transverse ribs 65 in the inner front corners of the spring cage, and which are preferably integral with the spring cage, and being in apposition respectively to the ribs 62 of the double faced spring seat. 45 Extending vertically through the forward corners of the spring cage are the perforations 66 suitably aligned with the grooves 64 in the ribs 65 to permit the reception of the stop bolts or keys 67 through the same, and within 50 the grooves 64. The stop bolts or keys 67 are each provided at the upper end with a head 68, and at the lower end are threaded to receive the nut 69.

In normal position of the parts of the 55 draft rigging, as illustrated in Fig. 2 of the drawings, the forward edge 70 of the collar 48 of the double faced spring seat is separated by a predetermined space from the rear ends of the friction shoes 38. In assembling the gear the friction cushioning mem-

bers are placed within the friction cylinder. The short connecting bolt, supplemental spring and double faced spring seat are placed within the shell. The main springs are then driven into place through the lateral openings of the spring cage, and an initial compression given the gear. The stop bolts, 67 are then slipped in, and serve to keep the main springs in a state of initial compression.

The transverse ribs 65 in the forward corners of the spring cage, and the transverse ribs 62 on the forward face of the double faced spring seat prevent the subjection of the stop bolts to bending moment, the said stop bolts being subjected only to pressure exerted by the oppositely arranged ribs of the spring cage and double faced spring seat. The connecting rod 55 extending as it does only between the wedge at one end and the double faced spring seat at the other permits the use of larger main springs of a higher compression resisting capacity than those which may be employed in connection with a connecting rod extending from the wedge 90 at one end to the rear end of the spring cage at the other.

I am also enabled by my invention to dispense with the use of a thimble between the double faced spring seat and the wedge. 95 The initial loading of the main spring, which is preferably greater than the compressed capacity of the supplemental spring 51, is maintained by the stop bolts 67.

The stop-bolts or keys 67—67 are in preferable construction accessible from without the spring-cage. The stop-bolts or keys serve to prevent the distortion of the spring-cage or shell under abnormal loads or shocks, as well as to keep the main springs 105 in a state of initial compression.

I claim:—

1. In a friction draft rigging the combination with a draw bar, draft yoke and stop members, a shell comprising a friction cylinder and a spring cage connected therewith, friction shoes and wedge within the friction cylinder, anti-friction rollers between said wedge and shoes, main springs within said spring cage, a two faced spring seat and a supplemental spring, of means to keep the main springs in a state of initial compression comprising stop bolts vertically disposed in the spring cage.

2. In a friction draft rigging, a combination with a draw-bar, draft-yoke and stop members, friction shell, friction cushioning members and main springs within the shell, a two-faced spring seat and a supplemental spring within said shell of means to keep the main springs in a state of initial compression, comprising keys arranged transversely of said shell and passing through the said shell.

3. In a friction draft rigging the combi-

nation with a longitudinally movable friction shell, of a wedge and friction shoes within the shell, a double faced spring seat, main springs engaging one side of said 5 spring seat, a supplemental spring interposed between the other side of said spring seat and the friction shoes, the said spring

seat being provided with bosses around which the said main springs are seated.

JOHN F. O'CONNOR.
